(57) **CLAIM**

The ornamental design for a fan, as shown and described.

DESCRIPTION

FIG. 1 is a front side elevational view of a fan embodying our new design;

FIG. 2 is a rear side elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a cross sectional view as seen along line 7—7 of FIG. 6, omitting the interior mechanism;

FIG. 8 is a perspective view as seen in the direction indicated by Arrow 8 in FIG. 2;

FIG. 9 is a perspective view as seen in the direction indicated by Arrow 9 in FIG. 2;

FIG. 10 is an enlarged cross sectional view as seen along line 10—10 of FIG. 2;

FIG. 11 is an enlarged cross sectional view as seen along line 11—11 of FIG. 2; and,

FIG. 12 is a perspective view for reference.

The broken line showing is included for the purpose of illustrating portions of the article and forms no part of the claimed design.
